Des. 211,887
Patented Aug. 6, 1968

211,887

TRAY FOR SOAP OR SIMILAR ARTICLE

Harry S. Dearling, 25 E. 83rd St.,
New York, N.Y. 10028

Filed Dec. 11, 1967, Ser. No. 9,729

Term of patent 14 years

(Cl. D33—24)

FIG. 1

FIG. 2

FIG. 4

FIGURE 1 is a perspective view of a tray for soap or similar articles showing my new design;

I claim:

The ornamental design for a tray for soap or similar article, as shown.
